UNITED STATES PATENT OFFICE.

INEZ L. HARMON, OF LOMA LINDA, AND STANLEY F. GIBBS, OF GLENDALE, CALIFORNIA.

SYRINGE-HOLDING CLIP.

Application filed February 19, 1925. Serial No. 10,298.

To all whom it may concern:

Be it known that we, INEZ L. HARMON and STANLEY F. GIBBS, citizens of the United States, residing at Loma Linda and Glendale, respectively, in the counties of San Bernardino and Los Angeles and State of California, have invented new and useful Improvements in Syringe-Holding Clips, of which the following is a specification.

10 This invention relates to syringe holding clips and particularly to a device for attachment to any ordinary type of fountain syringe which will retain the nozzle of the syringe when not in use above the water level in the water container.

15 A further object is to provide a syringe holding spring clip member providing security of the nozzle when placed in the spring clip member facilitating ready removal of the nozzle if desired.

It is readily apparent that the value of such a device lies in the disposal of the nozzle above the water level in the fountain syringe container to prevent a siphon of the water or inadvertent leaking of water through the nozzle.

20 Other objects and advantages will be made manifest in the following specification of an embodiment of the invention illustrated in the accompanying drawings, in which:

Figure 1 is a perspective view of a fountain syringe provided with the syringe holding clip.

25 Figure 2 is a perspective view of the syringe holding clip as seen when disengaged.

30 Figure 3 is a vertical side view of a particular type of spring clip member employed.

35 Figure 4 is a perspective view of a rubber fountain syringe with the syringe holding clip attached.

40 Figure 5 is a side view of a modified form of syringe holding clip.

45 The details of construction and use of the invention are as follows:

An ordinary type of fountain syringe water container 1 as illustrated in Figure 1 being formed with a flat back 2 and a semi-circular front 3 is adapted to rest upon a shelf or hang upon a hook in the usual manner. A nipple 4 at the lower end provides a connection with rubber tubing 5 which conducts water from the container and discharges it through nozzle 6. Ordinarily

there is no provision for disposal of the nozzle when not in use except by laying the rubber tubing over the top or the handle of the water container. To remedy this a syringe holding clip is formed of a straight strap 10 preferably a metal strap and this is bent at its upper end to form a hook 11. Adjacent the upper end of the strap 10 is fastened a transverse member 12 which is curved in a semi-circular form 60 enclosing the hook 11 and adapted to conform to the semi-circular front 3 of the water container 1. This transverse member may be welded, soldered, riveted or fastened by any suitable means to the straight strap 10. A clip member 13 is formed of resilient material such as a metal spring strap. The clip member 13 has a straight portion 14 and is bent in an upward and diagonal direction as at 15, then straight 65 upwardly again as at 16. The upper end of the clip member is bifurcated by being split vertically into two sections 17 and 18 from the top a part of the way to the straight portion 16. The section 17 is curved 70 outwardly and inwardly to form a semi-circular shape and terminates at the upper end with a short outwardly bent lip 20. The section 18 is bent into a semi-circular shape and formed with a lip 21, so that the opposing sections 17 and 18 provide an opening into which an object having a substantially circular diameter may be inserted. The lips 20 and 21 are adapted to 75 act as guideways for the article to be inserted. As the clip member 13 is made of spring material the sections 17 and 18 are adapted to accommodate themselves to the nozzles of various sizes and to firmly 80 grasp whatever nozzle may be placed therein. The clip member 13 is secured to the straight strap 10 by any suitable means 85 such as soldering or riveting.

The use of the invention is very simple. The hook 11 is placed over the rim 25 of the water container 1 and the semi-circular transverse member 12 is pushed against the front 3 and engaged under the bead 26 of the water container. Thus the hook will 90 support the syringe holding clip and the transverse member 12 fitting against the bead of the water container will prevent the clip from being disconnected.

The syringe nozzle 6 may be pressed 95 against the lips 20 and 21 of the spring clip 100

member 13 and the spring sections 17 and 18 will yieldably accommodate the nozzle 6 within the circular enclosure formed by them. It will be observed that a restriction 5 27 for preventing the dislodgment of the nozzle 6 is provided by the curvature of the sections 17 and 18.

The water container illustrated in Figure 4 is of rubber and has a lip 30, a neck 31, a 10 flat side 32 and a discharge opening 33. The 15 syringe holding clip may be hooked over the rim 30; the transverse member 12 laid adjacent the neck 31 and the straight strap 10 extended vertically against the flat side 32. It will be seen that where the syringe holding 20 clip is employed with a rubber fountain syringe the length of the straight strap 10 provides an added support for holding the clip in position as the side 32 of the container is naturally somewhat yielding.

It is obvious that the clip member 13 might be secured to the water container 1 in the manufacture of the water container without the employment of the straight 25 strap 10 and the transverse member 12.

In the modified form of syringe holding clip illustrated in Figure 5 a clamping member 40 is formed with a loop 41 adapted to accommodate the bead 26 of the water container 1, and a tongue 42 extends downwardly and terminates in a flare 43. The 30 body of the syringe holding clip comprises a continuation 44 of the clamp member 40

and a vertical shank 45 which is split at the upper end to provide a pair of spring clip members 46 and 47. It is apparent that the clamp member 40 needs merely to be pressed over the bead 26 and downwardly until the loop 41 surrounds the bead 26, and the tongue 42 pressing against the wall of the 35 water container will retain the syringe holding clip in position.

Various changes may be made without departing from the spirit of the invention as 40 claimed.

What is claimed is:

1. A syringe holding clip comprising a support adapted to hook over the rim of a container, and a clip member spaced from said support having a bifurcated upper end 50 forming two spring sections curved oppositely to form a clip for holding a nozzle in horizontal position.

2. A syringe holding clip consisting of a unitary strip of spring metal having one 55 end bent upon itself to form a hook adapted to fit over the rim of a container, an intermediate spacing arm, and a nozzle holding end split longitudinally to form two 60 arms bent in the shape of a substantially circular opening for holding a nozzle in horizontal position.

In testimony whereof we have signed our names to this specification.

INEZ L. HARMON.
STANLEY F. GIBBS.
